UNITED STATES PATENT OFFICE.

JAMES TIMMS, OF COLUMBUS, OHIO.

CAR-COUPING.

SPECIFICATION forming part of Letters Patent No. 624,707, dated May 9, 1899.

Application filed August 17, 1898. Serial No. 688,830. (No model.)

To all whom it may concern:

Be it known that I, JAMES TIMMS, of Columbus, in the county of Franklin and State of Ohio, have invented certain new and useful 5 Improvements in Car-Couplings; and I do hereby declare the following to be a full, clear, and exact description of the invention, such as will enable others skilled in the art to which it appertains to make and use the same.

10 My invention relates to an improvement in car-couplings; and it consists in the parts and combinations of parts, as will be more fully described, and pointed out in the claims.

In the accompanying drawings, Figure 1 is 15 a view in horizontal section of a coupling embodying my invention. Fig. 2 is a vertical sectional view on the lines 1 1 of Fig. 1 looking to the front. Fig. 3 is a view in perspective of the knuckle and locking pin and block. Fig. 4 is a view in side elevation of the pin 20 and block. Fig. 5 is a view in cross-section on the line 2 2 of Fig. 4 looking down. Fig. 6 is a view in section on the line 3 3 of Fig. 4 looking up.

25 A represents the draw-bar of the coupling; B, the draw-head; C, the guard-arm, and D the knuckle pivoted to the head by the pin D'. The inner end or tongue D² of the knuckle operates in the chamber of the draw-head 30 and is provided on its rear face or side with an extension or projection a, the upper face of which latter is inclined downwardly toward its rear end, forming an inclined surface b, on which the locking-block rides in coupling 35 and uncoupling. When the knuckle is open, I prefer to have the free end of the extension a rest under the block, and as the knuckle moves to a closed position the locking-block will be elevated by the inclined face b suffi- 40 ciently high to permit the tongue D² to pass under the block. The front edge of the tongue D² is provided with an incline c, which extends upwardly from a point adjacent to the front edge of the tongue D². The reverse 45 inclines b and c are separated by a plane surface d, on which the block rides during a portion of the movement of the tongue of the knuckle and operates to prevent the hook on the pin, which will be more fully described 50 later on, from reengaging its support during the act of coupling or uncoupling.

The draw-head B is provided in its top and

bottom faces with angular openings for the passage of the angular pin F. This pin is angular in cross-section and is provided at 55 its upper end with an opening f for the attachment of a lifting lever or chain and at a point below the opening with a flange g, which latter is adapted to rest on the flange g', surrounding the opening in the upper face of the 60 head, and limit the downward movement of the pin. The upper section G of the pin is cut away, as at h, forming a hook h', which latter is adapted to engage the flange g' at one side of the pin-opening for holding the 65 pin in its elevated position. The portion G' of the pin below the hook h' is cut away on two adjacent sides, as shown in dotted lines in Figs. 1 and 6, thus reducing the diameter of the pin below the shoulder h³, which latter 70 is formed by cutting away the two sides of the pin.

The reduced portion G' of the pin F is 75 adapted to receive the block I, which latter rests and moves within the throat of the coupling-head. The block I is secured on the pin by a key I', which latter holds the block solidly against the shoulder h³ and absolutely prevents any independent movement of the block on the pin, and as the pin is angular in 80 cross-section and the pin-holes in the coupling-head of the same shape it follows that the block has no movement whatever independently of the pin.

The locking-pin F closely fits the pin-hole 85 in the coupling-head; but when the pin is raised, as will be hereinafter described, to its highest position the portion h thereof, cut away to form the hook h', rests in line with the top wall of the coupling-head, and thus 90 permits the pin to move laterally, so as to bring the hook h' over the side flange g', and when in this position the pin holds the block in its elevated position to permit the unrestricted forward movement of the tongue D². 95

The block I is approximately rectangular in cross-section, its longest diameter being from front to rear. This block rests in a seat or guideway formed in the coupling-head, and in addition to being guided in its vertical movements by the inner side walls of the head it is provided on its rear side with a projecting rib i, which latter bears against a shoul-

- der i' within the throat of the coupling-head and assists in preventing lateral movement of the block. The base of the throat of the draw-head is also provided with a seat, (clearly shown in Fig. 2,) which latter receives the lower end of the block and sustains and supports same when the pressure of the tongue of the knuckle is against the block, as it is when the coupling is in its locked position.
- 10 The front face of the block is cut away at its lower front and inner edge to form shoulders J and J', which are preferably somewhat rounded and inclined, against which the rear end of the tongue makes contact when the 15 knuckle is turned from its open or unlocked position to a closed or locked position, and vice versa. The end of projection a may be of such length that it never passes completely from under the inclined surface.
- 20 Hence when the knuckle is open the block rests upon the end a' of the knuckle, and as the inclined face b of the projection on the tongue of the knuckle is in contact with the shoulder J of the block it follows that a closing 25 movement of the knuckle operates to elevate the block and pin carried thereby sufficiently high for the tongue of the knuckle to pass thereunder, and after they have passed the block falls to its closed position, as shown 30 in Fig. 2, in front of the knuckle and locks the knuckle securely in position.

The tongue is provided on its edge with a rib K, which latter when the knuckle is in its closed position alines with a groove K' in 35 the block I. Hence when the block falls to lock the knuckle this rib enters the groove in the block and operates as a stop against outward movement of the knuckle in the event the pivot-pin should break, or, in other words, 40 it holds the knuckle against displacement irrespective of the pivot-pin.

To open the knuckle, the locking-pin is first elevated, and if it is desired to hold it elevated, as is frequently the case while shifting 45 cars, it can be tilted so as to bring the hook h' over the flange g', as shown in dotted lines in Fig. 2. This holds the pin and block elevated and leaves the knuckle free to open as soon as the car which is pushing same slacks 50 its speed. While the block is in its elevated position, the lower face of the cut-away portion of the block rests on and in advance of the forward incline c of the tongue. Hence as the tongue moves forwardly under the 55 block the incline c engages the shoulder J' of the block, lifts and tilts the same and the coupling-pin carried thereby, and carries the hook from off the flange g', thus leaving the pin and block free to fall. As the tongue 60 moves forwardly the block descends and, as before stated, rests on the rear inclined end b of the tongue. In coupling the cars the block is elevated by the movement of the inclined tongue b under the same, and the instant the front of the tongue passes the block 65 the latter falls and locks the knuckle in its closed position.

The inclines b and c are separated by the plane surface d, on which the block rides, while one incline has passed from under the block and the other is moving toward the block. This plane surface simply holds the block steady and in an upright position after the hook on the locking-pin has been released from the flange and prevents it from rebounding and again engaging the flange.

If the pin and block be held elevated by the engagement of the hook on the pin with the flange on the head, the engagement of the rear incline b on the rear extension of the tongue of the knuckle will by its engagement with the shoulder J on the block tilt the pin and block, thus disengaging the hook and permitting the block to fall in front of the tongue.

The block is provided with the rib i, before referred to, and also with the rib i². These ribs are located on opposite sides of the pin-hole in the block and are adapted when the block is in its lowest position to pass through 90 slots in the lower face of the coupling. A key passed through a slot in the pin and bearing against these ribs locks the block solidly on the pin.

From the foregoing it will be seen that if 95 the knuckle be open and the locking-block down the inward movement of the knuckle elevates the block, and after the knuckle has reached its closed position the block falls and locks it solidly in place. To release the 100 knuckle, the pin and block are elevated, and if it be desired to hold the block elevated, as is frequently the case in making flying switches, the outward or opening movement of the tongue of the knuckle operates to release the block and allow same to fall behind the tongue ready to be elevated by the inward movement of the tongue on the knuckle. If, on the other hand, the block be elevated 110 while the knuckle is open, the tongue of the latter will, as before described, while moving to a closed position trip the block, thus causing same to fall in front of the tongue and lock the knuckle.

It is evident that changes in the construction and relative arrangement of the several parts might be made without avoiding my invention, and hence I would have it understood that I do not restrict myself to the particular construction and arrangement of parts 115 shown and described; but,

Having fully described my invention, what I claim as new, and desire to secure by Letters Patent, is—

1. In a car-coupling of the vertical-plane 125 type, the combination with a head and a knuckle the tongue of the latter having a vertical face adapted to engage the locking-block and reverse inclines on its upper surface, of a vertically-sliding locking-block having an undercut portion adapted to be engaged by the inclines on the tongue whereby the block is elevated by engagement with one incline and adapted when supported in an

elevated position to be released by the other incline.

2. In a car-coupling of the vertical-plane type, the combination with a head and a knuckle, the latter provided with reverse inclines on its tongue, of a vertically-sliding block suitably supported within the head and provided on its lower inner edge with a shoulder, the said locking-block adapted to be elevated by the engagement of one inclined surface on the tongue with the shoulder on the block and adapted when supported in an elevated position to be tripped by the other incline on the tongue.

15 3. A knuckle for car-couplings having a tongue provided on its upper free end with reverse inclines and a smooth flat surface between and connecting the inclines.

4. In a car-coupling of the vertical-plane type, the combination with a head and a knuckle the latter provided with an incline on its rear end, of a locking-pin carrying a locking-block and having a bearing in the upper and lower faces of the head, the block having a shoulder at its front inner edge, the said shoulder adapted to be engaged by the incline on the knuckle for elevating the block, and means for temporarily holding the pin and block elevated in a position to be engaged 30 and released by the knuckle passing under same.

5. In a car-coupling of the vertical-plane type, the combination with a head and a knuckle the latter having a tongue with a cam-shaped end, of a locking-pin having bearings in the upper and lower faces of the head, a locking-block removably secured on said pin, and a key secured to the pin below the block.

40 6. In a car-coupling the combination with a head and a knuckle, the latter having a tongue with reverse inclines thereon and a plane surface between the inclines, of a vertically-sliding locking-pin, a block carried by said pin and cut away at its lower inner edge, and means for securing said block to the pin.

45 7. In a car-coupling, the combination with a

coupling-head and knuckle, the tongue of the latter being provided on its rear side edge with an upwardly and rearwardly inclined 50 surface, of a pin constructed to have a tilting movement transversely to the draw-head, and provided with a hook adapted when the pin is raised to engage the upper wall of the draw-head and to be upheld thereby, and a block carried by the pin, said block being provided with an inclined shoulder which is engaged by the knuckle when swung into its closed position, whereby the pin when in its raised position is elevated and tilted into a 60 position to drop and lock the knuckle when the latter is swung into its closed position, substantially as set forth.

8. In a car-coupling, the combination with a coupling-head and knuckle the tongue of the latter being provided on its front side edge with an inclined surface, of a pin constructed to have a tilting movement transversely to the draw-head and provided with a hook adapted when the pin is raised to hook over a raised 65 projection on the upper wall of the draw-head and to be upheld thereby, and a block carried by the pin, said block being provided with an inclined shoulder which is engaged by the knuckle when swung from its closed to its open 70 position, whereby the pin when in its raised position is elevated and tilted into a position to drop, when the knuckle is swung into its open position, substantially as set forth.

9. In a car-coupling the combination with a 80 draw-head and knuckle, the tongue of which is provided with a vertical lip or rib, of a locking pin and block carried thereby, the block being provided with a vertical groove within which the lip on the tongue interlocks when 85 the knuckle is in its closed and locked position, substantially as set forth.

In testimony whereof I have signed this specification in the presence of two subscribing witnesses.

JAMES TIMMS.
